UNITED STATES PATENT OFFICE.

THOMAS ALLATT, OF WEST NEW BRIGHTON, NEW YORK, ASSIGNOR TO HERRMANN, AUKAM & CO., OF NEW YORK, N. Y., A CORPORATION OF NEW YORK.

TEARING-MACHINE.

1,180,363.

Specification of Letters Patent. Patented Apr. 25, 1916.

Application filed November 30, 1914. Serial No. 874,626.

To all whom it may concern:

Be it known that I, THOMAS ALLATT, a British subject, and a resident of West New Brighton, in the county of Richmond, city 5 and State of New York, have invented a certain new and useful Tearing-Machine, of which the following is a specification.

My invention comprises means for tearing cloth; particularly, means for tearing cloth 10 transversely or parallel with the woof or filling threads. It is particularly designed for use in the making of handkerchiefs and other small piece goods from long strips of fabric.

As is well known to those skilled in the art, it is preferable to tear certain kinds of cloth, particularly linen cloth, rather than to cut it, for the woof threads are not always exactly at right angles to the warp 15 threads, and if such fabric be cut, the cut may cross and sever some of the woof threads, whereas if the fabric be torn, the tear will follow the woof threads without crossing them. Heretofore, in the production 20 of handkerchiefs and the like from linen fabric, it has been customary to tear such fabric transversely by hand, because of the above stated advantage of tearing, as distinguished from cutting, and this hand-tear- 25 ing has been a slow and laborious operation. By the machine herein illustrated and described the tearing is done automatically, and at a speed such that one machine can do 30 the work of a very great many hand operatives.

My invention consists in mechanical means for tearing a strip of fabric transversely, and at regular or spaced intervals; in means for regulating the distance between 35 successive points of tear; in the novel tearing mechanism herein described; and in various other features, as hereinafter described and particularly pointed out in the appended claims.

The objects of my invention are to provide automatic means for tearing cloth transversely and at spaced intervals; to provide means for adjusting the distance between successive points of tear; to provide 45 efficient tearing means; and generally to produce a machine which is simple, easily operated, and capable of high speed operation.

I will now proceed to describe my invention with reference to the accompanying

drawings, and will then point out the novel 55 features in claims.

In said drawings: Figure 1 shows a top view of my tearing machine, a portion of the frame and of the adjustable table of the machine being broken away. Fig. 2 shows a 60 central longitudinal vertical section of the machine. Fig. 3 shows a transverse vertical section of the machine on the line $x-x$ of Fig. 2. Fig. 4 shows a side elevation of the machine, parts being broken away the same 65 as in Fig. 1. Fig. 5 shows a detail side view of a portion of the mechanism employed for adjusting the distance between successive tears, and Fig. 6 shows an end view of the same parts. Fig. 7 is a fragmentary perspective elevation of one of the tearers in action, showing how it passes through the fabric and how the fabric passes over that 70 tearer. Fig. 8 shows a top view of one of the tearer carriages, detached from the machine, and with the corresponding tearer slide mounted thereon; also the cloth clamping mechanism of the carriage. Fig. 8^a is a detail side elevation of the cam which 75 controls the action of the cutter which nicks the fabric to facilitate the initiation of the tear, and which controls the pad covering the 80 tearer. Fig. 9 shows a central vertical section of the same parts on the line $y-y$ of Fig. 8. Fig. 10 shows a fragmentary longitudinal section of the discharge end portions 85 of the machine, on a scale larger than Fig. 2, and illustrates particularly the action of the transverse tearer-feed cam and return cam on the tearer slide; and Fig. 11 shows an 90 end view of the parts shown in Fig. 10, a portion of the frame of the machine being shown in section. Fig. 12 is a view similar to Fig. 10, of the receiving end of the machine. Fig. 13 shows a transverse vertical 95 section of the machine on the line $z-z$ of Fig. 12; and Fig. 14 shows a fragmentary horizontal section on the line $w-w$ of Fig. 12. Fig. 15 is a fragmentary perspective elevation of the supplemental adjusting device employed for making fine adjustments of the distance between tears. Fig. 16 is a 1 face view of one of the cams which control the gripper fingers.

In this machine there are a plurality of 105 tearer carriages mounted on an endless conveyer of the belt-chain type, such carriages located at spaced intervals along such car-

rier; which intervals are adjustable. The belt or chain carrier is mounted on sprocket wheels, one pair of which sprocket wheels also serve to drive the chain carrier. The 5 tearer carriages are provided with gripper fingers, automatically opened and closed, which fingers open to permit the passage of fabric between said fingers and gripping surfaces of the carriage and then close on 10 the fabric, so holding the fabric and feeding it forward as the carrier moves. In practice, I prefer to hold the fabric at one edge only, and so provide gripper fingers at one side only of each carriage. A tearer 15 is mounted on each carriage to move transversely of the machine from one side of the carriage to the other. This tearer consists of a shoe acting initially at that edge of the fabric held by the gripper fingers and 20 acting initially about midway between such gripper fingers. Preferably I provide this tearer with a cutter which is caused to nick the fabric at the edge to facilitate the initiation of the tear. The tearer is moved 25 along its carriage, and therefore across the fabric to be torn, by a stationary oblique cam, which encounters a projection of that tearer as the tearer is carried along the machine by the said belt or chain carrier. 30 After the completion of the tear the gripper fingers are opened to permit the severed piece of the fabric to drop. During the return motion of each carriage (as that carriage passes along the upper run of the 35 carrier) the tearer of that carriage is returned by a similar oblique cam.

In the drawings, numeral 1 designates a suitable machine frame provided with fixed 40 bearings for a sprocket shaft 2, and with guides for a longitudinally adjustable support 3 upon which are supports for a fixed sprocket-carrying shaft 4, adjustable longitudinally of the machine. Shafts 2 and 4 each carry two sprocket wheels 5, located 45 near the sides of the machine, the sprockets on shaft 4 being loose thereon, and over these sprocket wheels run link chains 6. For purposes of adjustment, as hereinafter 50 described, the chains 6 are not continuous, in the actual structure, but are each composed of a plurality of sections, corresponding sections of the two chains being connected by transverse tearer-carriages as hereinafter described, though the structure is such that 55 the effect is the same, during the operation of the machine, as if such chains 6 were continuous. Each length of the chains 6 is provided, as illustrated particularly in Figs. 1, 2, 3 and 8-14 inclusive, with a tearer 60 carriage comprising two properly spaced transverse clamping bars 7 extending across the machine to the opposite and corresponding chain-section 6; these bars 7 constituting means to which the fabric may be clamped 65 (by means hereinafter described) for feed-

ing said fabric, and for holding the fabric during the action of a corresponding tearer which, as hereinafter described, is mounted upon a slide arranged to travel, transversely of the machine, along said carriage on guide 70 rods 8 provided in connection with said bars 7; (see particularly Fig. 14). The chains, and said carriages, constitute endless chain-carriers.

Each tearer comprises a slide or base 9 (Figs. 8, 9 and 14) having sliding bearings through which the guide rods 8 pass, whereby said base 9 may slide over said rods 8; and upon this base 9 is mounted an inclined tearing shoe 10, constituting the 80 tearer proper, having in it a slot 11 through which the end of a cutting knife 12 may project; (in Fig. 9 this knife is shown in retracted position). During the tearing operation the tearer projects downward 85 from its carriage, in the inverted position shown in Fig. 7, since the cloth to be torn passes beneath the plane of the lower runs of chains 6. Fig. 9 shows the tearer in the position occupied during return movement, 90 i. e., upright. As the tearer starts to move from left to right of the machine (as the parts are viewed, for example, in Figs. 8 and 9) the edge of the fabric encounters the edge 13 of the knife 12 (then raised slightly 95 from the position shown in Fig. 8, by a cam 14—Figs. 8 and 8^a) and such knife makes a slight cut in the edge of the fabric, and then is permitted, by the cam 14, to drop to the position shown in Fig. 9, the 100 fabric riding up on the shoe 10, and being torn thereby. A pad 15, usually of leather or like flexible yet durable material, covers the slot 11, being carried by a support 16 pivoted to a lever 18 at 17. The fabric passes between this pad 15 and the shoe 10, said pad holding the fabric down upon the shoe 10 and so enforcing tearing of the 105 fabric by said shoe. The cutting knife 12 is carried by the lever 18 forming a part of the support 16 for the pad 15, and it will be seen that when the cam 14, acting upon the roller 19 on the end of the lever 18, raises the knife 12 (when the tearer is at the extreme left hand side of the machine) it also raises the pad 15 to facilitate the passage of 110 the edge of the fabric between said pad and the shoe. When the cam 14 permits the knife 13 to drop, it also causes the pad 15 to drop upon the fabric. This pad 15 holds the cloth smooth and taut during the passage of the shoe 10 through it.

Cloth to be torn comes from the right of the machine as viewed in Figs. 1 and 2, for example, passing over the table 20 and thence to the undersides of the chains 6, and beneath the first pair of transverse gripping bars 7. These gripping bars carry pivoted gripping fingers 21 (Figs. 8 and 9). Each gripping finger 21 is pivoted at 22 to 115 120 125 130

its corresponding gripping bar 7 and has a rear extension provided with a slot 23 in which works a roller 24 mounted on a plate 25 pivoted at 26 to an extension 27 of the corresponding gripping bar 7 and having a pivotal connection 28 to a slide rod 29, mounted to slide upon the corresponding gripping bar 7, and provided with a spring 30 tending to pull it outward; which tendency communicated through the roller 24 to the upper edge of the slot 23 of gripping finger 21, tends to press that gripping finger down against the gripping bar 7 or against material between that gripping bar 7 and gripping finger 21. As the gripping bars 7 pass downward over the front sprocket wheels 5, a roller 31 carried by a cross-piece 32 connecting two corresponding slide bars 29, encounters a fixed cam 33 (Figs. 14 and 20) carried by the shaft 4 (which shaft does not rotate), and by the cam the roller 31 is forced inward or to the right of Figs. 8 and 9, thereby causing the corresponding plates 25 to open or raise the gripping fingers 21. The cam 33 is of such shape that this opening movement is gradual. As the gripping fingers 21 pass around beneath the fabric the cam 33 releases the roller 31 and slide bars 29, permitting the springs 30 to draw such slide bars slightly to the left of Figs. 8 and 9, so closing the fingers 21 on the fabric and holding such fabric between such gripping fingers 21 and the gripping bars 7. Naturally, as movement of the tearer carriages to the left of Figs. 1 and 2 and 12 continues, the fabric will be drawn onward. Gripping fingers 21 are provided on one side of the machine only, as I find it desirable to have the fabric held on one side only and loose on the other side. Shortly after the fabric is thus gripped by two gripping fingers mounted on a pair of gripping bars 7, a roller 34 projecting upward (with the parts in the position then occupied) from the tearer slide 9, encounters an oblique feed cam 35, having the form of a diagonal angle bar, curved slightly at its initial end. This cam 35 presses the tearer across the machine, causing the cutting knife 12 to cut the fabric slightly at the edge and then retire, as previously explained, and then forcing the tearer shoe 10 into the cut just formed, and causing that tearer to rip or tear the fabric transversely. The incline of the cam 35 is such as to carry the tearer to the opposite side of the machine before the gripping bars 7 carrying such tearer have reached the rear sprockets 5. It will be seen that by the operation of the tearer as described, the fabric is torn completely across. As the gripper bars 7 pass around the rear sprockets 5, another cam 36 similar to cam 33 previously mentioned, encounters the roller 31, so opening or raising the gripping fingers 21, and permitting the piece of fabric so torn off from the main strip of fabric to drop; after which the said gripping fingers 21 again drop. As the pair of gripping bars 7, the progress of which has been followed as above, pass over the top of the machine, the roller 34 of the tearer pertaining to such pair of gripping bars, encounters another oblique cam 37, whereby that tearer is returned to the right hand side of the machine (as viewed in Fig. 3). This return cam 37, like the feed cam 35, is curved slightly at its initial end, for the purpose of accelerating the tearer gradually. It will be noted that during the tearing operation the cloth is held at the side of the machine at which the tear starts, and on each side of the point at which the tear starts. There being nothing to confine the cloth beyond the point at which the tear starts the tear will follow the transverse threads of the fabric.

Each tearer carriage, formed by a pair of gripping bars 7 and associated parts, is provided at both ends with rollers 38 which ride upon angle irons 39 (Fig. 13) attached to the frame of the machine; the weight of the carriage being thereby carried by the angle irons and rollers. Other rollers 40 carried by each carriage, and bearing against the sides of angle irons 39, take the end thrust produced in feeding the tearers across the machine.

In order to facilitate introducing a strip of cloth into the machine at the starting of operations, each carriage is provided with a hook 41 (Figs. 12 and 13) which is engaged with the end of the strip of fabric to draw the strip through the machine. In practice, with two carriages in the position indicated in Fig. 12, one just above the sprocket wheels 5, and the other just below such sprocket wheels, the end of the fabric would be engaged with the hook 41 of the upper carriage. Then, the machine being started, as this upper carriage passes around the sprockets 5, to the under side of said sprockets, it will draw the fabric with it, (the gripping fingers of that carriage being open,) so avoiding any occasion for the operator to insert his hands into this portion of the machine. After the gripping fingers 21 have gripped the fabric, it is of course immaterial that the end portion of the fabric is still held by the hook; for the small portion of the fabric between the end and the first tear is wasted. As the gripping fingers are released from the fabric at the discharge end of the machine, the severed lengths of fabric drop.

As will be understood readily, the machine illustrated is adaptable for acting upon fabric strips of different widths, without adjustment. But it is frequently desirable to adjust the distance between successive tears; for handkerchiefs are square. as a

rule. To this end each of the chains 6 is composed of a plurality of chain sections, as previously stated. One end of each chain section 6 is secured rigidly between two projecting plates 42, forming a support for a sprocket wheel 43, the other end of such chain section being secured to the sprocket wheel 43 next beyond and passing more or less completely around such sprocket wheel.

10 Each sprocket wheel 43 is locked, normally, by a pin 44 engaging between teeth of such sprocket wheel, such locking pin 44 being carried by a stirrup 45 mounted upon a rod 46 extending transversely of the machine from near one chain 6 to near the opposite chain 6. Springs 47 tend to hold the pins 44 in engagement with the sprocket wheels; but when it is desired to change the adjustment of distance between tears, the stirrups 15 45 of the several locking pins may be moved inward against the springs 47, and the sprocket wheels 43 may then be rotated to take up or let out as many chain links as desired, and then the pins 44 reengaged 20 with the sprocket wheels. The shaft 4 is mounted upon a sliding support 3, as previously explained; and as the chains 6 are drawn up or let out, as the case may be, this support 3 is shifted longitudinally in or out 25 as required. To facilitate drawing the chains taut after adjustment, further sprocket chains 48 are provided on the two sides of the machine, said chains passing over sprocket wheels 49 and 50, the shaft 51 30 upon which sprocket wheels 49 are mounted extending across the machine so that both sprocket chains 48 will move alike. The table or support 3 is connected to these sprocket chains 48 by brackets 52. A ratchet 35 wheel 53 (Figs. 4, 5 and 6) is drivingly connected to one of the sprocket wheels 50 and a lever 54 is provided with a pawl 55 adapted to engage the teeth of this ratchet wheel. Pull rods 56 and a chain 57 connect arm 54 40 to a foot treadle 58. A spring 59 tends to raise this treadle and also to move the arm 54 to the right of Figs. 4 and 5. A locking screw 60 normally prevents any motion of lever 54. It will be apparent that if this 45 locking screw 60 be unscrewed, the spring 59 will draw the arm 54 to the right of Fig. 4. Pressure of the foot upon treadle 58 will then move the arm 54 to the left, so causing pawl 55 to actuate the ratchet wheel 53, and 50 one or two or three strokes of this treadle will ordinarily suffice to draw the chains 6 taut; after which the screw 60 may be turned in to lock the parts. The sprocket wheels 43 and locking pins 44 therefore, permit of adjustment of distance between tears by increments equal to the pitch of the chain; but it is sometimes desirable to provide for still finer adjustment of distance between tears. To this end each tearer carriage, formed by 55 gripping bars 7 and associated parts, is pro-

vided with a hinged plate 61, also with a vertically adjustable slide plate 62 mounted upon the hinge plate 61 (see Figs. 13 and 15) which plate 62 is provided with the extension 63 adapted to engage the fabric 70 from one edge thereof for a short distance inward from such edge. The plate 61 is connected by the pin 64 and link 65 to the adjacent rod 46 above mentioned. This adjusting device 61-65 operates to vary the 75 length of fabric held between the gripping device of adjacent carriages, without change of distance between such carriages, in that its extension 63 constitutes a projection which holds that fabric out of what would 80 otherwise be a straight line connecting the gripping device of adjacent carriages. Since the shortest distance between two points is along a straight line connecting those points, anything carried by a tearer-carriage 7-7 85 which holds the fabric away from such straight line increases the length of fabric held between the gripping devices of adjacent carriages. It will be apparent that by adjusting the position of the slide plate 62 90 with respect to the plate 61, the additional length of fabric between the gripping devices of adjacent carriages may be varied. The adjustment of plate 62 to plate 61 constitutes means for the very exact adjustment 95 to precisely the length of fabric desired between successive tears. The connection of the plate 61 by link 65 to the rod 46 causes the plate 61 to assume the angular position shown at the right of Fig. 12 and shown in 100 Fig. 15, and so prevents the extension 63 from acting upon the fabric until, the corresponding tearer carriage having reached the bottom of the chain carrier 6-6 and having been carried slightly beyond the 105 sprockets 5 at the front end of the machine, the gripper fingers 21 of that carriage have closed upon the fabric.

It sometimes happens that, as a piece of the cloth which has been torn off drops, a woof 110 thread or threads of this cloth will be caught in the tearer, causing the piece of cloth to hang from the tearer. To sever any such connection I have provided cutting means shown particularly in Figs. 10 and 11 and 115 comprising shear blades 66 and 67, the former of which is secured to a fixed bracket 68, while shear blade 67 is pivoted at 69 to the bracket 68 and is connected at 70 to a bent lever 71 mounted upon a rock shaft 72 120 provided with an arm 73 adapted to be actuated by rollers 74 carried by extensions 75 of the tearer carriages. After the roller 74 of each tearer carriage encounters the arm 73, just before that tearer carriage passes 125 around the rear sprockets 5, the shear blade 67 is actuated, so severing any such threads connecting the severed piece of fabric with the tearer of that carriage. As will be noted, this cutting mechanism is located 130

near that side of the machine at which the tearer finishes its operation, viz:—the side of the machine opposite that at which the gripper fingers 21 are located.

5 It sometimes happens that that edge of the fabric at which the tearer emerges is not a selvage edge. In such case it may happen that the tearer, as it emerges from such edge of the fabric will pull with it one or 10 two threads from the edge of the fabric. It is desired that these threads also shall be severed by the shear blades 66 and 67. To that end guides 76 are provided on the carriages, which will carry such edge-threads 15 between the shear blades 66 and 67. These guides, in the construction shown, are small rods, extending obliquely from that transverse bar 7 of each carriage which is adjacent the front edge of each piece of fabric to be torn, and which inclines backwardly with respect to the direction of progress of the fabric. Such guides 76 will engage threads connecting the corresponding tearer with outer-edge threads of the fabric and will 20 guide them between the shear blades 66 and 67, so causing said shear blades to sever such threads. Under some conditions it is possible that pressure might be brought to bear on these guides 76 in such way as to 25 bend them, if provision were not made to permit yielding. To this end each guide 76 is connected to its corresponding tearer carriage by a spring hinge 77, as indicated particularly in Figs. 1, 2, 3, 8 and 10. This hinge permits yielding in the direction indicated by the dotted arrow 77 in Fig. 10.

The machine is driven by power applied to sprocket shaft 2. For this purpose I have indicated, in Fig. 1, a belt wheel 78 mounted 40 upon that sprocket shaft.

What I claim is:—

1. A tearing machine comprising means for feeding material to be torn through the machine, in combination with means for 45 tearing such material transversely at spaced intervals, comprising a tearer movable transversely across the material, and means for so moving said tearer.

2. A tearing machine comprising means for feeding material to be torn through the machine, in combination with means for tearing such material transversely at spaced intervals, comprising a tearer movable transversely across the material, means for so 50 moving said tearer, and means for returning said tearer to its initial position.

3. A tearing machine comprising a continuously movable carrier having means for gripping the material to be torn, in combination with tearing means movable across 55 such material while so held.

4. A tearing machine comprising a continuously movable carrier having means for gripping the material to be torn, in combination with tearing means movable across 60

such material while so held, comprising a tearer movable transversely across the material, and means for so moving said tearer.

5. A tearing machine comprising a continuously movable carrier having means for gripping the material to be torn, in combination with tearing means movable across such material while so held, comprising a tearer movable transversely across the material, means for so moving said tearer, 75 and means for returning said tearer to its initial position.

6. In a tearing machine, the combination with an endless movable carrier, and a tearer carriage movable with such carrier, of a 80 tearer mounted on such carriage to move transversely of the material, and along such carriage.

7. In a tearing machine, the combination with an endless movable carrier, and a 85 tearer carriage movable with such carrier, of a tearer mounted on such carriage to move transversely of the material, and along such carriage, and means for so moving said tearer.

8. In a tearing machine, the combination with an endless movable carrier, and a tearer carriage movable with such carrier, of a tearer mounted on such carriage to move transversely of the material, and along such 95 carriage, means for so moving said tearer, and means for returning said tearer to its initial position.

9. In a tearing machine, the combination with an endless movable carrier, and a tearer carriage movable with such carrier, of a tearer mounted on such carriage to move transversely of the material, and along such carriage, and a cam for so moving said 100 tearer.

10. In a tearing machine, the combination with an endless movable carrier, and a tearer carriage movable with such carrier, of a tearer mounted on such carriage to move transversely of the material, and along such carriage, and two cams, one for moving the tearer along the carriage during the tearing 110 operation, the other for returning the tearer.

11. In a tearing machine, the combination with an endless movable carrier, and a tearer carriage movable with such carrier, of a tearer mounted on such carriage to move transversely of the material, and along such carriage, and a fixed oblique cam arranged to be encountered by the tearer during the 115 movement of the carriage and thereby to cause movement of the tearer along such carriage.

12. In a tearing machine, the combination with an endless movable carrier, and a tearer carriage movable with such carrier, of a tearer mounted on such carriage to move transversely of the material, and along such carriage, and two fixed oblique cams arranged to be engaged successively by the 125 130

- tearer during the movement of the carriage and thereby to move the tearer transversely along the carriage and then to return it.
13. In a tearing machine, the combination with an endless movable carrier of the belt type, and supporting means therefor, such carrier comprising a tearer carriage, of a tearer mounted on such carriage to move transversely of the material to be torn, and along such carriage, means for so moving said tearer during the advance motion of its carriage, and means for returning the carrier during the return motion of the carriage.
14. In a tearing machine, the combination with an endless movable carrier of the belt type, and supporting means therefor, such carrier comprising a tearer carriage, of a tearer mounted on such carriage to move transversely of the material to be torn, and along such carriage, an oblique cam arranged to engage the tearer during the advance movement of the carriage and thereby to cause transverse movement of the tearer along such carriage, and means for returning the tearer arranged to act thereon during the return movement of the carriage.
15. In a tearing machine, the combination with an endless movable carrier of the belt type, and supporting means therefor, such carrier comprising a tearer carriage, of a tearer mounted on such carriage to move transversely of the material to be torn, and along such carriage, an oblique cam arranged to engage the tearer during the advance movement of the carriage and thereby to cause transverse movement of the tearer along such carriage, and another oblique cam arranged to act upon the tearer during the return motion of the carriage, and thereby to return said tearer.
16. In a tearing machine, the combination with a tearer carriage having a guide for the tearer, of a tearer mounted on such guide and adapted to be moved therealong.
17. In a tearing machine, the combination with a tearer carriage having a guide for the tearer, of a tearer mounted on such guide and adapted to be moved therealong, and comprising an inclined shoe forming the tearer proper.
18. In a tearing machine, the combination with a tearer carriage having a guide for the tearer, of a tearer mounted on such guide and adapted to be moved therealong, and comprising a rounded inclined shoe forming the tearer proper.
19. In a tearing machine, the combination with a tearer carriage having a guide for the tearer, of a tearer mounted on such guide and adapted to be moved therealong, comprising an inclined shoe forming the tearer proper, and means for holding the material to be torn against such shoe.
20. In a tearing machine, the combination

with a tearer carriage having a guide for the tearer, of a tearer mounted on such guide and adapted to be moved therealong, comprising an inclined shoe forming the tearer proper, said shoe having a knife aperture, and a cutting knife mounted to be projected through such aperture.

21. In a tearing machine, the combination with a tearer carriage, of a tearer mounted to move along such carriage, a cutter mounted in connection with such tearer to engage the material to be torn, and means arranged to hold such cutter in operative position at the initiation of the tearing movement, and thereafter to retire such cutter.

22. In a tearing machine, the combination with a tearer carriage, and a tearer movable therealong, and having in it a cutter-aperture, of a cutter adapted to work in such aperture, and means for holding such cutter in operative position at the beginning of the tearing operation and thereafter to retire said cutter.

23. In a tearing machine, the combination with a tearer carriage, and a tearer movable therealong, and having in it a cutter-aperture, of a cutter adapted to work in such aperture, means for holding such cutter in operative position at the beginning of the tearing operation and thereafter to retire said cutter, and means, covering such cutter aperture, adapted to hold the material to be torn against the tearer.

24. In a tearing machine, the combination with tearing means, of cutting means arranged to engage the edge of the material to be torn at the initiation of the tearing operation, and thereby to cut the fabric to facilitate the initiation of the tearing operation.

25. In a tearing machine, the combination with means for feeding material to be torn through the machine, and tearing means arranged to tear such material transversely, of means for nicking one edge of the fabric to facilitate initiation of the tear.

26. In a tearing machine, the combination with means for feeding material to be torn through the machine, and tearing means arranged to tear such material transversely, of cutting means comprising a movable cutter and operating means therefor arranged to advance such cutter to nick the fabric prior to the initiation of the tear, and then to retire such cutter.

27. In a tearing machine, the combination of one or more tearing mechanisms, and means for carrying such tearing mechanism or mechanisms in the direction of progress of material to be torn, and then returning the same, of gripping means carried by such tearing mechanism or mechanisms, and automatic means for causing such gripping means to grasp the material to be torn and subsequently to release the torn material.

28. In a tearing machine, the combination of an endless carrier, rotatable supporting wheels over which such carrier passes, and one or more tearing mechanisms carried by such endless carrier, and comprising gripping means and automatic operating means therefor.
29. In a tearing machine, the combination of an endless carrier, rotatable supporting wheels over which such carrier passes, and one or more tearing mechanisms carried by such endless carrier, comprising gripping means and automatic operating means therefor, and cam means arranged to actuate such gripping means to grasp the fabric.
30. In a tearing machine, the combination of an endless carrier, rotatable supporting wheels over which such carrier passes, and one or more tearing mechanisms carried by such endless carrier, comprising gripping means and automatic operating means therefor, and cam means arranged to actuate such gripping means to grasp the fabric and subsequently to again actuate such gripping means to release the torn fabric.
31. In a tearing machine, the combination of an endless carrier, rotatable supporting wheels over which such carrier passes, and one or more tearing mechanisms carried by such endless carrier, comprising gripping means and automatic operating means therefor, and cam means arranged to actuate such gripping means to grasp the fabric and subsequently to again actuate such gripping means to release the torn fabric, such cam means arranged to actuate the gripping means in the first instance during the passage of such gripping means around one of said carrying wheels.
32. In a tearing machine, the combination of an endless carrier, supporting means therefor, one or more tearer-carriages carried by such carrier and extending across the same, and comprising gripper bars, gripper fingers carried by said gripper bars, and means for raising said gripper fingers and for pressing said gripper fingers against the gripper bars.
33. In a tearing machine, a tearer carriage comprising a fixed clamping member in combination with a pivoted gripper finger adapted to hold material to be torn between it and said clamping member, and operating means for said gripper finger comprising a member mounted to slide on said carriage, a spring for actuating said sliding member in one direction, said sliding member provided with means for moving it in opposition to such spring, and means connecting said sliding member to the gripper finger to cause opening and closing of said gripper finger.
34. In a tearing machine, a tearer carriage comprising a fixed clamping member in combination with a pivoted gripper finger adapted to hold material to be torn between it and said clamping member, said gripper finger having a slotted rear extension, and operating means for said gripper finger comprising a member mounted to slide on the carriage, a spring for moving said sliding member in one direction, said sliding member being provided with means for moving it in opposition to said spring, and a pivoted member connected to said sliding member and provided with means engaging the slot of said gripper finger, whereby motion of said sliding member actuates said gripper finger.
35. In a tearing machine, a tearer carriage adapted to be moved bodily and comprising a fixed clamping member in combination with a pivoted gripper finger adapted to hold material to be torn between it and said clamping member, and means for actuating said gripper finger comprising a member mounted for movement on said carriage, and means connecting said movable member to said gripper finger whereby movement of said movable member actuates said gripper finger, said movable member having a projection adapted to be engaged as the carriage moves and to be moved along the carriage by reason of such engagement.
36. In a tearing machine, a tearer carriage, and means for moving the same bodily, said carriage provided with a clamping member and with a pivoted gripper finger adapted to hold material between it and said clamping member, operating means for said gripper finger comprising a member mounted to move upon said carriage, and provided with a projection whereby it may be moved, means connecting said movable member to said gripper finger whereby movement of said movable member actuates said gripper finger, in combination with means adapted to engage such projection as the carriage moves to cause actuation of said gripper finger.
37. In a tearing machine, the combination of an endless carrier, means for supporting the same, and one or more tearer-carriages mounted upon said carrier to be moved thereby, such carriage or carriages provided with supporting wheels, and fixed tracks along which such wheels may run.
38. In a tearing machine, the combination of an endless carrier, supporting means therefor, one or more tearer carriages mounted upon such carrier to be moved thereby, a tearer mounted upon each such carriage and movable therealong, means for so moving such tearer and means for receiving the end thrust due to the movement of such tearer.
39. In a tearing machine, the combination of an endless carrier, supporting means therefor, one or more tearer carriages mounted upon such carrier to be moved thereby, a tearer mounted upon each such

carriage and movable therealong, means for so moving such tearer, each such carriage provided with wheels for receiving the end thrust due to the motion of such tearer, and 5 fixed tracks along which such wheels may run.

40. A tearing machine comprising in combination an endless carrier, means for supporting the same, a plurality of separate 10 tearing means mounted upon such carrier at spaced intervals, and means for varying the distance between said tearers.

41. A tearing machine comprising in combination an endless conveyer and supporting 15 means therefor, said conveyer composed of a plurality of conveyer sections, and means for connecting such sections comprising winding drum carriers each secured to one end of one of said conveyer sections, and a 20 winding drum mounted upon each such carrier and having the end portion of the next conveyer section secured to it, and means for locking such winding drums in various positions, whereby the effective length of each 25 such section may be varied as desired.

42. A tearing machine comprising in combination an endless conveyer and supporting means therefor, said conveyer composed of a plurality of chain sections, and means for 30 connecting such sections comprising winding-sprocket carriers each secured to one end of one of said chain sections, and a winding sprocket mounted upon each such carrier and having the end portion of the next chain 35 section secured to it, and means for locking such winding sprockets in various positions, whereby the effective length of each such chain section may be varied as desired.

43. A tearing machine comprising in combination an endless carrier composed of a plurality of adjustable carrier sections, and means for varying the effective length of each such carrier section, supporting wheels 40 for said carrier and means for varying the distance between said supporting wheels in accordance with variation of the effective 45 length of the carrier sections, and a plurality of tearing means each mounted upon a separate section of such carrier, whereby 50 by varying the effective length of the carrier sections and the distance between the supporting wheels of such carrier, the distance between successive tearing means may be varied.

55. 44. In a tearing machine, a tearer car-

riage, in combination with a tearer adapted to move along such carriage, a cover for such tearer, a cutter adapted to act initially on the fabric to be torn, a common swinging support for said cover and cutter, and automatic means for first moving such cutter into operative position and raising the cutter, and then for retracting the cutter and moving the cover toward the tearer. 60

45. A tearing machine comprising in combination means for feeding material to be torn through the machine, a tearer adapted to tear the material transversely, and automatic holding means arranged to hold the material on opposite sides of the line of intended tear. 65

46. A tearing machine comprising in combination means for feeding material to be torn through the machine, a tearer adapted to tear the material transversely, and automatic holding means arranged to hold the material on opposite sides of the line of intended tear and to grasp the fabric 70 at that edge only at which the tear is initiated. 75

47. A tearing machine comprising in combination, means for feeding material to be torn through the machine, a tearer adapted to tear the material transversely, and means adapted to sever a thread or threads of the 80 material acted upon which may cling to the tearer. 85

48. A tearing machine comprising in combination, means for feeding material to be torn through the machine, a tearer adapted to tear the material transversely, means 90 adapted to sever a thread or threads of the material acted upon which may cling to the tearer, and means for guiding such threads to said severing means. 95

49. A tearing machine comprising in combination, means for feeding material to be torn through the machine, a tearer adapted to tear the material transversely, means adapted to sever a thread or threads of the 100 material acted upon which may cling to the tearer and yielding means for guiding such threads to said severing means.

In testimony whereof I have signed this specification in the presence of two subscribing 105 witnesses.

THOMAS ALLATT.
